UNITED STATES PATENT OFFICE

170,641

LIST FINDER

William Lang, Verona, N. J., assignor to The
Bates Manufacturing Company, Orange, N. J.,
a corporation of New Jersey

Application April 7, 1953, Serial No. 24,391

Term of patent 14 years

(Cl. D74—1)

To all whom it may concern:

Be it known that I, William Lang, a citizen of the United States of America, residing at Verona, county of Essex and State of New Jersey, have invented a new, original, and ornamental Design for a List Finder, of which the following is a specification, reference being had to the accompanying drawing forming a part thereof:

Figure 1 is a top plan view of a list finder showing my new design;

Figure 2 is a front end elevational view of the list finder shown in Figure 1;

Figure 3 is a side elevational view;

Figure 4 is a side elevational view of the side opposite to that shown in Figure 3; and

Figure 5 is a rear end elevational view thereof.

I claim:

The ornamental design for a list finder, as shown.

WILLIAM LANG.
